UNITED STATES PATENT OFFICE

2,106,903

GAS MIXER

Albert Tonkin, Cloquet, Minn., assignor of two-thirds to J. L. Monahan, Minneapolis, Minn.

Application March 27, 1936, Serial No. 71,185

4 Claims. (Cl. 48—180)

This invention relates to gas mixers for internal combustion engines, and has special reference to improvements in one particularly adapted for use in feeding natural or similar gas to such an engine.

The principal object of the invention is to provide a more practical and efficient carburetor for this purpose than heretofore known.

Another object is to provide such a gas mixer having means automatically operable by the gas mixer when in action and hydraulically controlled.

Other objects and advantages of the invention will appear in the following description thereof.

Referring now to the accompanying drawing, forming part of this application, and wherein like reference characters indicate like parts.

Figure 1 is a vertical central sectional view of one of the improved gas mixers.

Figure 2 is a transverse sectional view on the line 2—2, Figure 1, with portions thereof in elevation for better comprehension.

My improved gas mixer comprises the main body portion 1 having three extensions 2, 3 and 4 therefrom, the extensions 2 and 4 being axially disposed and of smaller diameter than the body 1 while the extension 3 is of substantially the same size as the body 1; all being cylindrical in construction. A transverse rotatable shaft is indicated at 5 for control of the supply throttle, and a parallel shaft indicated at 6 passes through the extension 4 for control of the butterfly valve 7, regulating the gas and air fuel supply to the engine, and common to such gas mixers. These two shafts are connected in the usual manner by the link 8 and levers 9 and 10 so as to function simultaneously.

The extension 3 embodies an automatic air supply to the gas mixer which is governed hydraulically and will be described later.

The gas supply connection is shown at 11, and the gas is fed into the extension 2 of the gas mixer through the port 12 and this port is controlled by the vertically reciprocable valve head 13 carrying the resilient valve cap or seat 14, this valve head being normally held in closed position by the two oppositely disposed expansive springs 15 and 16, the pressure of the spring 15 being controlled by the adjustable plug 17. The lower stem 18 of the valve head 13 extends within the spring housing 19 which is mounted upon the eccentric 20 keyed to the shaft 5 so that rotation of the shaft 5 will raise and lower the valve head during the throttling of the gas mixer.

While this construction of throttling the valve may be old, one of the novel features of the instant

invention resides in the air intake mounted within the extension 3, and which is provided with a removable sleeve 21 slid into the extension 3 and which sleeve has a tapered or conically shaped bore 22; the outlet of the bore in the outer end of the sleeve being circular and controlled by the valve 23 which is reciprocably carried upon the piston rod 24 attached to the sleeve piston 25 within the cylinder 26. The tapered bore 22 of the sleeve 21 is for the purpose of regulating the volume of air as the valve 23 is reciprocated; that is to say the farther the valve 23 is opened, the ratio of the space for admission of the air is progressively increased, and, of course, the reverse occurs when the valve is being closed.

Within the cylinder 26 and upon both sides of the piston 25 is carried suitable oil for modifying the action of the piston when it is operated, and as the oil must be transferred from one end to the other of the cylinder when the piston is reciprocated a passageway or by-pass 28 is provided, it being obvious that the reciprocation inwardly of the piston rod is accomplished by the vacuum of the engine, while it is held normally outwardly by the expansive spring 27 carried about the piston rod 24, within the innermost end of the cylinder 26. It will be noted that the head of the piston 25 is perforated and normally closed by a small spring controlled washer-like valve 29 which will be released on outward motion of the piston but close on inward motion thereof, and, the cylinder 26 being full of oil, any movement inwardly of the piston as caused by the suction of the engine not shown will necessitate travel of the oil from the spring engaged side of the piston through the port or passageway 28 to the opposite end of the piston, whereas when return action of the piston occurs the oil will readily pass through the perforated head thereof. As a control means for the passage of oil from one end of the cylinder to the other I have shown the manually operated needle valve 29, the adjustment of which will regulate the flow of oil through the by-pass 28.

It will be noted, too, that the cylinder 26 is an extension of the cup-like previous member 30 which is screw-threadedly mounted upon the outer extremity of the extension 3 and forms holding means for the sleeve 21, having the frusto-conically shaped bore 22 therein.

From the above it is evident that I have provided an efficient and practical form of gas mixer designed for use in connection with natural or other similar gas and having an automatically adjustable hydraulically controlled air supply.

therefor, which forms a principal novel feature of the invention.

Having thus described my invention, what I claim and desire to secure by Letters Patent, is:

- 5 1. The combination with a fuel gas and air mixer having a main mixing chamber provided with gas inlet and discharge ports, an air inlet chamber communicating with said main mixing chamber intermediate of said gas inlet and discharge ports, a valve for control of said air inlet including a piston carrying rod, a cylinder within which said piston reciprocates, an expansive spring within said cylinder intermediate of the piston and head of the cylinder towards said valve to normally keep the latter closed, said cylinder being adapted to contain a body of oil positioned upon both sides of said piston, an oil by-pass from one end of the cylinder to the other and a manually adjustable valve within said by-pass to regulate the flow of oil from one end of said cylinder to the other and thus control the action of said valve.
- 10 2. The combination with a gas mixer of the character described having a main mixing chamber provided with gas inlet and discharge ports, an air inlet chamber communicating with said main mixing chamber intermediate of said gas inlet and discharge ports, a valve to control the amount of air passing through said air inlet including a piston carrying rod, a cylinder within

which the piston reciprocates, said cylinder being adapted to contain a body of oil to retard the action of said piston, and spring means to hold the valve normally closed.

3. The combination with a gas mixer of the character described having a main mixing chamber provided with gas inlet and discharge ports communicating therewith, an air inlet chamber intermediate of said gas inlet and discharge ports, a valve to control the amount of air passing through said air inlet, a cylinder adapted to contain a body of oil, a piston within the cylinder, a rod connecting the valve and piston, means for holding the valve normally closed, said piston being retarded by the action of the oil in said cylinder, and means to vary the retarding influence of said oil.

4. The combination with a fuel gas and air mixer having a main mixing chamber provided with gas inlet and discharge ports, an air inlet chamber communicating with said main mixing chamber, a valve for control of said air inlet including a piston carrying rod, a cylinder adapted to contain a body of oil and within which said piston reciprocates, a spring about the rod to normally keep the valve closed, and a manually adjustable oil by-pass to regulate the flow of oil therein from one end of the cylinder to the other and thereby control the action of the valve.

ALBERT TONKIN. 30
